US00D992936S

(12) **United States Design Patent** (10) **Patent No.:** **US D992,936 S**
(45) **Date of Patent:** **** Jul. 25, 2023**

(54) **DISPLAY STAND**

(71) Applicant: **Hanvon Ugee Technology Co., Ltd.,**
Shenzhen (CN)

(72) Inventor: **Ethan Scott Ouimet**, Vancouver, WA
(US)

(**) Term: **15 Years**

(21) Appl. No.: **29/806,146**

(22) Filed: **Sep. 1, 2021**

(30) **Foreign Application Priority Data**

Jun. 28, 2021 (CN) 202130401403.8

(51) **LOC (14) Cl.** **06-04**

(52) **U.S. Cl.**

(57) **CLAIM**

The ornamental design for a display stand, as shown and described.

DESCRIPTION

FIG. 1 is a front perspective view of a display stand of the present disclosure;

FIG. 2 is a rear perspective view thereof;

FIG. 3 is a bottom perspective view thereof;

FIG. 4 is a front elevational view thereof;

FIG. 5 is a rear elevational view thereof;

FIG. 6 is a left-side elevational view thereof;

FIG. 7 is a right-side elevational view thereof;

FIG. 8 is a top plan view thereof; and,

FIG. 9 is a bottom plan view thereof.

Any shading or cross-hatching are not features of the design but are utilized to illustrate the surface contours of the display stand design in the drawings.

1 Claim, 9 Drawing Sheets
